UNITED STATES PATENT OFFICE.

BERT O. TILDEN, OF NEW YORK, N. Y., ASSIGNOR TO AMERICAN SANITARY WORKS, OF NEW YORK, N. Y., A CORPORATION OF NEW JERSEY.

DESIGN FOR A WATER-CLOSET SEAT AND COVER.

42,985.

Specification for Design.

Patented Sept. 3, 1912.

Application filed January 27, 1910. Serial No. 540,462. Term of patent 14 years.

To all whom it may concern:

Be it known that I, BERT O. TILDEN, a citizen of the United States, residing at New York, in the county of New York and State of New York, have invented a new, original, and ornamental Design for a Water-Closet Seat and Cover, of which the following is a specification, reference being had to the accompanying drawing, forming part thereof.

The figure is a perspective view of a water closet seat and cover, the seat having a flat top surface and sides extending at right

angles thereto and formed with square-cut top and bottom edges, the seat being surmounted by a cover having a flat top surface and sides extending at right-angles thereto with square-cut top and bottom edges, the whole constituting my design.

I claim:

The ornamental design for a water closet seat and cover, as shown and described.

BERT O. TILDEN. [L. S.]
